UNITED STATES PATENT OFFICE

95,452

DESIGN FOR AN APRON

Ada Quinn, Ogden, Utah

Application April 17, 1934, Serial No. 51,437

Term of patent 7 years

To all whom it may concern:

Be it known that I, Ada Quinn, a citizen of the United States, residing at Ogden, in the county of Weber and State of Utah, have invented a new, original, and ornamental Design for an Apron, of which the following is a specification, reference being had to the accompanying drawing, forming part thereof.

The figure of the drawing is a plan view of an apron with the neck portion extended to show the complete neck opening.

The strings fragmentarily shown at the waistline of the apron extend to the length essential to adapt the apron to the size of the wearer.

The panel, which forms the back of the apron when it is put on, extends to the length to fit the size of the wearer.

I claim:

The ornamental design for an apron, as shown and described.

ADA QUINN.
